UNITED STATES PATENT OFFICE.

ANTHONY E. CARLSON, OF LOS ANGELES, CALIFORNIA.

RAILWAY CROSSING.

Application filed July 8, 1926. Serial No. 121,159.

My invention relates to improvements in railroad crossing in which the rails cross one another at any angle or curve, in conjunction with double swinging frog members; and the objects of my improvements are, first, to provide a continuous running surface for car wheels to roll over, with clearance for the flange of the said car wheel to pass through; second, to afford facilities for the adjustment or renewal of any worn or broken parts independently of the connecting track-rails leading to the said railroad crossing; and, third, to reduce the pounding of the wheels to a minimum as they roll from one rail to the other on the said crossing at any speed, and to prevent broken rails or flat car wheels.

A further object of my invention is to provide a noiseless crossing which may be manually, mechanically or automatically operated.

I attain these objects by the mechanism illustrated in the accompanying drawing, in which:

Figure 1 is a plan view of my crossing showing the frogs in normal open and closed positions.

Figure 2 is a sectional view of my crossing on line 2-2 of Figure 1.

Figure 3 is a sectional view of my crossing on line 3-3 of Figure 1.

Figure 4 is a modified form of a flexible connecting bar between the frogs.

Referring to the drawings in which like characters of reference designate similar parts, 1 represents a plate with rails 3 and 4 secured thereon, the faces 24 and 23 form the inner sides of the rails 3 and 4 respectively, and may be set to any angle or curve in a railway crossing, where the same is to be used, the said rails 3 being joined together at their points 25, the two rails 4 being in turn extended in a line adjoining with the said rails 3, the faces 17^b being curved on the inner ends of the said rails 4, and the faces 17^a swinging inwardly on a line adjoining the outer faces 17^b on the rails 4 to the said faces 23 thereon, with the pins 7 as the center of the said curved faces, and the said faces 17^b forming tangents between the said faces 23 and 24, the frogs 2^a and 2^b are operatively secured on the pins 7 between the said faces 24 and 17^b, the pins 7 being secured to the plate 1, and the faces 17^a are curved around the said pins 7 as centers, to correspond operatively with the

said faces 17^b. The straight faces 10 form the sides of the frogs 2^a and 2^b and the rollers 5 at points extending from the pins 7 to the faces 17^a, and the said rollers 5 are 60 operatively positioned in the frogs 2^a and 2^b respectively. The companion frogs 12 and 13 are operatively connected to the said frogs 2^a and 2^b respectively. The faces 11 are formed on the companion frogs 12 and 13 and the rollers 5, so as to be positioned at an angle to the faces 23 when the companion frogs 12 or 13 and the rollers 5 are held in a closed position, as shown in Figure 1, and when the faces 10 and 24 are positioned parallel to one another the said companion frogs 12 and 13 are held in an open position, 70 as shown in Figure 1. Again, the faces 11 are formed on the companion frogs 12 and 13 and the rollers 5 so as to be positioned at an angle to the faces 23 when the said frogs 2^a and 2^b, and companion frogs 12 and 13, are held in a closed position. The companion frog 12 is extended operatively 75 under the companion frog 13 on the plate 1, 80 and the companion frog 13 is in turn extended operatively over the companion frog 12, with the groove 16 positioned flush with the face 17^a, between the frog 2^b and the companion frog 13. The sockets 15 and the keys 85 14 are integral with the inner portions of the said companion frogs 12 and 13, and mesh together when the said frogs 2^a and 2^b are in their open positions, as shown in Figure 1.

The teeth 8 are formed on the outer face of the said frogs 2^a, 2^b, 12 and 13, between the pins 7 and 19 and the rails 4, and the teeth 9 are in turn formed in the said plate 1 and mesh operatively with the teeth 8 95 with said pins 7 and 19 as the respective centers.

The bar 6 is operatively secured between the frogs 2^a and 2^b at such points to hold one pair of frogs 2^b and companion frog 13 100 in an open position and the other pair of frogs 2^a and companion frog 12 in a closed position, as shown in Figure 1, and a spring 22 is also substituted, as shown in Figure 4, when a bar 6 is formed in two sections. 105

In the operation of my railway crossing the frog 2^a and the companion frog 12, and the opposite frog 2^b and the companion frog 13 are held in relative open and closed positions as hereinbefore described by the bar 6, 110 thus holding the faces 10 and 11 to the faces 24 and 23 respectively at angles to one an-

other, and as a car wheel rolls over the rails 3 from either direction over their points 25 towards the rails 4, the flange on the said car wheel wedges between the faces 24 and 10, and spreads either one of the frogs 2^a or 2^b into an open position, depending upon the direction from which the said wheel is rolling, and the bar 6 in turn pulls the opposite set of frogs 2^a or 2^b into a closed position. Thus by spreading the faces 10 on the frogs 2^a and 2^b, from the faces 24 on the rails 3, an unbroken rolling surface is provided over the rail 3, the frog 2^a and the rail 4, in one direction, and the rail 3, the frog 2^b and the rail 4 in the crossing direction. When the said car wheel is rolling from the opposite direction to those hereinbefore described, beginning from the rails 4, thence over the frogs 2^a or 2^b, to the rails 3, the flange of the car wheel first rolls between the faces 23 and 11, and spreads either the companion frogs 13 or 12 into open positions, and thus an unbroken rolling surface is provided over the rail 4, the frog 2^a and the rail 3, in one direction, and over the rail 4, the frog 2^b and the rail 3 in the crossing direction.

The groove 16 provides a passage for the flange of the car wheel to pass through when rolling over the frog 2^b.

When the flange of the said wheel spreads the faces 10 or 11 from the faces 24 or 23 respectively the rollers 5 revolve in the direction of the rolling of the said flange, and the friction by the wedging effect therebetween is eliminated.

The teeth 8 on the said frogs 2^a—2^b and companion frogs 12—13 mesh slidably with the teeth 9 on the plate 1 with the pins 7 and 19 respectively as their centers, to form an unbroken joint therebetween over the top surfaces of the said frogs 2^a—2^b, the companion frogs 12—13, and the plate 1 respectively.

When the bar 6 is split in two sections on line 30, as shown in Figure 4, the spring 22 is secured to the two sections thereof in a tension position to hold the same together under normal operation conditions, and should an obstruction occur between any of the working parts to cause the frogs 2^a—2^b and companion frogs 12—13 to function independently of one another, the said bar 6 will spread against the tension of the said spring 22 and give an automatic relief until the said obstruction is removed.

Having thus described my invention what I claim is:

1. In a railway crossing of the class described, a plate support, two joined rails pointed together, two adjoining rails dis-

posed in alinement with the said joined rails, mounted on the said plate, a pair of frogs operatively positioned between the said joined rails and the adjoining rails, respectively, and companion frogs operatively positioned in connection with the said frogs, a roller means, adapted to be positioned operatively in the said frogs and companion frogs adjacent to the said rails and adjoining rails, a set of teeth formed in the said frogs and companion frogs and in the said plate, adapted to be meshed operatively together, an operating means connected to the said frogs and companion frogs, adapted to flexibly hold one frog and its companion frog in an open position and the other frog and its companion frog in a closed position, as set forth.

2. In a railway crossing of the class described, a plate support, two joined rails pointed together, two adjoining rails disposed in alinement with the said joined rails, mounted on the said plate, a pair of frogs operatively positioned between the said joined rails and the adjoining rails, respectively, and companion frogs operatively positioned in connection with the said frogs, a roller means, adapted to be positioned operatively in the said frogs and companion frogs adjacent to the said rails and adjoining rails, a set of teeth formed in the said frogs and companion frogs and in the said plate, adapted to be meshed operatively together, an operating means connected to the said frogs and companion frogs, adapted to flexibly hold one frog and its companion frog in an open position and the other frog and its companion frog in a closed position, as set forth.

3. In a railway crossing, a pair of frogs operatively associated with a pair of intersecting rails of said crossing, a bar connected at its ends to said frogs respectively, said bar being divided between its ends into two sections, one of which sections being connected to one frog and the other section connected to the other frog, and a spring surrounding said rod and connected at its ends to the sections respectively of the rod, said rod and spring being arranged to hold one frog in open position and the other frog in closed position.

In testimony whereof I affix my signature.

ANTHONY E. CARLSON.
